(57) **CLAIM**

The ornamental design for a wrist brace with a thumb attachment, as shown and described.

DESCRIPTION

FIG. 1 is a frontal plan view of a wrist brace with a thumb attachment, showing our design.

FIG. 2 is a top elevational view of the wrist brace embodiment of FIG. 1.

FIG. 3 is a bottom elevational view of the wrist brace embodiment of FIG. 1.

FIG. 4 is a first side elevational view of the wrist brace embodiment of FIG. 1.

FIG. 5 is a second side elevational view of the wrist brace embodiment of FIG. 1.

FIG. 6 is a first perspective view of the wrist brace embodiment of FIG. 1 in an open configuration; and,

FIG. 7 is a second perspective view of the wrist brace embodiment of FIG. 1 in a closed configuration.

The broken lines are included for the purpose of illustrating environmental structure and form no part of the claimed design.

1 Claim, 3 Drawing Sheets
